UNITED STATES PATENT OFFICE

132,855

DESIGN FOR A MEMORIAL GRAVE MARKER

Otto H. Harer, Painesville, Ohio

Application November 24, 1941, Serial No. 104,284

Term of patent 14 years

To all whom it may concern:

Be it known that I, Otto H. Harer, a citizen of the United States, residing at Painesville, in the county of Lake and State of Ohio, have invented a new, original, and ornamental Design for a Memorial Grave Marker, of which the following is a specification, reference being had to the accompanying drawing, forming part thereof.

In the drawing:

Fig. 1 is a top plan view of a memorial grave marker, showing my new design.

Fig. 2 is a section taken on line 2—2 of Fig. 1.

I claim:

The ornamental design for a memorial grave marker, as shown.

OTTO H. HARER.
